UNITED STATES PATENT OFFICE.

WILLIAM JORDAN, OF MINNEAPOLIS, MINNESOTA.

GRAIN-DOOR.

No. 926,494.

Specification of Letters Patent. Patented June 29, 1909.

Application filed December 7, 1908. Serial No. 466,311.

To all whom it may concern:

Be it known that I, WILLIAM JORDAN, of Minneapolis, Hennepin county, Minnesota, have invented certain new and useful Improvements in Grain-Doors, of which the following is a specification.

My invention relates to grain doors for freight cars and the object of the invention is to provide a door, which will effectually prevent the escape of grain in transit and be capable of movement out of the door opening when it is desired to discharge the car of its contents.

A further object is to provide a door of compact construction, which, when not in use, will be partially concealed and thoroughly protected when the car is in use for other purposes than the hauling of grain.

Other objects of the invention will appear from the following detailed description.

The invention consists generally in various constructions and combinations all as herein-after described and particularly pointed out in the claims.

In the accompanying drawings forming part of this specification, Figure 1 is an outside view of the doorway of a freight car, showing my invention applied thereto. Fig. 2 is a vertical, sectional view of the same. Fig. 3 is a detail, sectional view of the doorway on the inside of the car. Fig. 4 is a vertical, sectional view, showing the door in its inoperative position. Fig. 5 is a similar view, illustrating the parts in position to permit the initial discharge of the grain.

In the drawing, 2 represents a freight car door frame, whereon I arrange suitable metallic guide-ways 3. The door, which slides vertically in these guide-ways, consists of a series of narrow slats 4 connected to one another by suitable hinges 5. These slats may be of any suitable width and thickness and the hinges are of a type, which will be flush substantially, with the surface of the door and will be protected thereby against injury. The sill 6 of the car, has a vertical slot 7 therein, extending across the doorway and of sufficient width to receive the flexible door. Beneath this sill on the cross beam 8 of the car, I provide a series of anti-friction guide rollers 9, which engage and support the door when it is lowered through the slots 7 to a point beneath the car floor. These anti-friction guide rollers may be arranged as shown in

Fig. 2, so that the lower portion of the door will be substantially horizontal when it is moved down to a point beneath the car floor or these rollers may be arranged as shown in Fig. 5 where a portion of them are mounted on a curved line and cause the rear portion of the door to swing upwardly toward the floor, instead of lying horizontally as in Fig. 2.

The door sill has a downwardly inclined surface 10 and a plate 11 is hinged at 12 on each side of the door opening, preferably near the casing and is of sufficient width to cover the slot 7 and normally prevent the entrance of the door, therein. This plate has a recess 13 in its upper surface to receive the lower edge of the door and form a tight joint therewith, preventing the escape of the grain at that point. This plate is normally held in a horizontal position by means of a shaft 14 having arms 15 with notched upper ends to engage the outer edge of the plate and hold it in a horizontal position, forming a continuation, substantially, of the car floor. The shaft 14 is provided with an operating crank 16, by means of which the arms 15 may be rocked out of engagement with the plate 11 to allow it to drop down upon the surface 10. The door is held against premature movement by means of pins 17 fitting loosely within holes in the guide-ways and in the ends of the door and preventing downward movement of the door when the supporting plate 11 is released. This release of the plate will take place when the operator desires to discharge the grain from the car. At that time, the shaft 14 will be rocked, releasing the plate 11 and allowing it to fall and expose an opening several inches in height, the full width of the door. Through this opening the grain will flow until its pressure on the door has been relieved, when the pins 17 will be removed and the door raised sufficiently to allow the plate 11 to be swung on its hinges into the car until it rests upon the car floor. The door may then be lowered through the slot 7 until it is entirely clear of the opening. The plate 11 will then be swung back over the slot in the sill and the discharge of the grain resumed until the car is entirely emptied of its contents.

I claim as my invention:

1. The combination, with a freight car, having a doorway and guide-ways therefor, said guide-ways extending beneath the car

- floor, of a flexible door vertically movable in said guide-ways, the sill beneath the door opening having a slot therein to receive said flexible door, and the top of said sill being 5 inclined, a plate hinged above said sill and adapted to extend across said slot and rest on said inclined surface, said plate in its normal raised position forming a continuation of the floor of the car and supporting 10 the flexible door, a space being provided between said door and said plate when the latter is dropped to rest on said inclined surface, a means for temporarily supporting said plate in its raised position, 15 substantially as described.
2. The combination, with a freight car having a doorway and guide-ways thereon, said guide-ways extending beneath the car floor, and the sill of the door way having a 20 slot therein, of a flexible door vertically movable in said guide-ways and in said slot, a plate hinged at its inner edge and normally covering the slot in said sill and having a limited vertical movement, means arranged 25 to support said plate in its raised position in contact with the lower edge of the door, said means allowing said plate to move downwardly and expose an opening under the door, for the purpose specified.
3. The combination, with a freight car having a door opening and guide-ways thereon and extending beneath the floor of the car, of a flexible door vertically movable in said guide-ways, a plate hinged at its 30 inner edge and projecting across said guide-way and adapted to engage and support the lower edge of the door when in a raised position, said plate having a vertical swinging movement and adapted to be raised to a level with the car floor and when lowered exposing an opening under the car door, and a rod arranged in front of said plate and having fingers adapted to engage the edge of the same, said rod being capable of rocking in its bearings to lift said fingers 35 and raise said plate or lower the fingers to allow said plate to drop to an inclined position.
4. The combination, with a freight car having a doorway and guide-ways thereon, 40 of a flexible door vertically movable in said guide-ways, a plate arranged to extend across said guide-ways within the door opening and temporarily engage the lower edge of the door, means engaging and supporting said plate in a substantially horizontal position, said means when disengaged from said plate permitting it to drop down to an inclined position away from the lower edge of the door and expose a discharge opening between said plate and door, 45 substantially as described.
- In witness whereof, I have hereunto set my hand this 24th day of November 1908.
- WILLIAM JORDAN.
